YARN TAKE-UP

Eugene St. Pierre, Pawtucket, R. I., assignor to
 Hemphill Company, Central Falls, R. I., a corporation of Massachusetts

Application March 20, 1945, Serial No. 583,721

8 Claims. (Cl. 66—146)

1

This invention relates to a new and useful improvement in yarn take-ups such as are used on knitting machines of the circular, independent needle type. Take-up mechanisms of the same general type are not new. One is disclosed in Patent #2,193,311. The take-up of this invention is superior to those already known primarily in a control of the tension of the take-up spring which varies its effective tension and adapts the take-up to the exacting requirements of fine gauge knitting such as the knitting of sheer ladies' stockings.

One form of the invention, designed for a circular, independent needle, knitting machine of the Banner type, is shown in the drawing of which:

Fig. 1 is a side elevation of a pair of take-ups and their controlling mechanism;

Fig. 2 is a plan view of similar scope; and

Fig. 3 is a view illustrating the free end of a take-up.

As many take-ups as desired may be used. They may be identical. Two are shown in the drawing, one in inoperative and one in operative position.

As shown in Fig. 1 the take-up consists of the usual light wire arm 1, identical with the similar arm 2 of the other take-up, the free end of which is bent down and terminates in a yarn guiding loop similar to loop 3 of the other take-up and through which the yarn passes on its way from the cone to the yarn lever.

The other end of arm 1 is fixed in a block 4 pivoted on a horizontal shaft 5. In the form shown block 4 is slotted as at 6 so that the take-up arm 1 can be slid into it sideways after which it is fixed in position by set screw 7. Extending rearwardly of block 4 is a tail 8 which may be integral with arm 1. This tail is offset laterally of arm 1 as best shown in Fig. 2. Below tail 8 is an arm 9 of substantially rectangular shape one end of which terminates in a loop 10 through which tail 8 passes.

On the frame 11 of the take-up is pivoted as at 12 a rocker 13, the other end 14 of which is adapted to be engaged and lifted by a cam 15 on a pattern drum 16. Intermediate the ends of rocker 13 is a clamp 17 consisting of a disc 18 and a screw 19 threaded into rocker 13. Arm 9 has a semi-circular bend 20 at this point and terminates in a substantially circular loop 21 around pivot 12. In this way, an adjustment is provided for arm 9 since it can be moved vertically towards and away from screw 19 within the limits of clamp 17.

2

At the bend 22 of arm 9 is attached a spring 23, the other end of which is fastened to any suitable fixed part of the machine frame. Normally the downward pull of spring 23 causes arm 8 to urge arm 1 upward against the resistance of the yarn. In so doing loop 10 at the end of arm 9 slides along tail 8. In this way, the effective length of tail 8 with respect to shaft 5 upon which the take-up is pivoted is varied so that the tension exerted by the spring is also varied from what it would be were the spring attached directly to the take-up as has been customary in the past. By shaping tail 8 in a suitable manner, as best shown in Fig. 1, the effect of spring 23 can be additionally adjusted. In former take-ups the spring had to be strong enough to lift the take-up arm quickly to its highest position, say 60 degrees or more above the horizontal. As a result, when the take-up arm moved down the tension of the spring increased constantly and unavoidably became too great within the working range of the take-up while knitting is being carried on.

When knitting extremely sheer fabric such as a ladies' stocking, very small errors in method, particularly those affecting the yarn, produce very noticeable fabric defects. It has been found that the tensioning effect of spring 23 upon take-up arm 1 should be substantially uniform throughout the movement of the take-up and, in some instances, should be lighter when the take-up is down than when it is raised so that the take-up will exert a negligible or minimum effect upon the yarn during knitting.

Often it is desirable that the lifting effect of spring 23 upon arm 1 should increase as the arm rises in spite of the decreasing actual tension of the spring. All of these things can be accomplished by the hook-up described above through the proper shaping and proportioning of arm 1, tail 8, arm 9 and spring 23. Since an infinite variety of conditions are met in the knitting of various fabrics these matters must and can be left for determination by those skilled in the art. The manner in which a take-up of this character operates is otherwise too well-known to require further description.

Whenever the take-up is to be made inoperative it is accomplished by rotating drum 16 so that cam 15 will be lifted by it. This raises arm 9 and permits arm 1 to drop to a horizontal position. This is the position shown for take-up arm 2, its arm 25 (the equivalent of arm 9) having been raised by lever 26 under the influence of cam 27 which is the equivalent of cam 15. The length

of upwardly extending part 28 of arm 25 is such that when this arm is raised, as just described, the bottom of loop 29 at its end will press against the underside of tail 30 thus locking the take-up in its down position. The length of each cam 15 and 27 is such that the respective rocker will continue to ride upon it and the corresponding take-up remain locked until it is to function again. In other words, the length and position of each of these cams and the rate of rotation of drum 16 corresponds with the timing of the knitting operation with which they are concerned.

Associated with each take-up and operating thereby is a yarn clamp which opposes the feeding of the yarn from the cone whenever the take-up rises beyond its normal range of operation during knitting. This consists of a pivoted arm 31, the front end of which constitutes an operating lever 32. The other end 33 of lever 31 is fixed to a similar end 34 of another lever, the other end 35 of which comprises one element of a yarn clamp. The other element of the clamp consists of a block 36, the upper end of which is in exact alignment with the lower edge of clamp element 35.

Block 4 which carries the take-up arm 1 is also provided with an extension 37 adapted to engage the end of arm 32 and swing it downward. When this occurs part 35 of the yarn clamp is swung up and away from part 36 so that the clamp has no effect upon the feeding of the yarn. This is the situation shown with respect to the take-up represented by arm 2. Part 38 of its yarn clamp has been swung away from the other part by the engagement of end 39 of block 40 with the end of arm 41, the equivalent of arm 32.

The clamp is closed when the take-up arm 1 reaches the position indicated in dotted line at 42 which is somewhat higher than its normal uppermost position while knitting is going on. Thus the yarn is free to be fed from the cone to the needles during knitting but will be clamped so that it cannot be fed from the cone whenever the take-up rises appreciably higher. The connection between ends 33 and 34 of the levers which operate each yarn clamp is by means of a screw or bolt 43 passing through elongated slots. Consequently, the position of part 35 of the clamp in relation to arm 33 can be varied so as to insure that the clamp operates efficiently and at the desired position of the take-up arm.

Part 36 of the yarn clamp is also mounted upon its support 44 so that it can be adjusted vertically and fixed at its correct position by a screw 45.

The entire take-up and its operating drum can be mounted in any desirable way. Here its bracket 11 is shown attached to the upright 46 which supports the bobbin stand and other parts of the upper part of the machine. Drum 16 may be operated by any suitable mechanism under the control of a pattern drum or any other suitable timing device.

I claim:

1. A yarn take-up for a knitting machine which includes an arm, one end of which is supported by a horizontal pivot so that it is swingable in a vertical plane, an extension of said arm, a lever associated therewith for swinging said arm upwardly and means associated with said lever for energizing said lever.

2. A yarn take-up for a knitting machine which includes an arm, one end of which is supported by a horizontal pivot so that it is swingable in a vertical plane, an extension of said arm, a lever associated therewith for swinging said arm

upwardly and resilient means associated with said lever for energizing said lever.

3. A yarn take-up for a knitting machine which includes an arm, one end of which is supported by a horizontal pivot so that it is swingable in a vertical plane, an extension of said arm, a lever associated therewith for swinging said arm upwardly, resilient means associated with said lever for energizing said lever and means for locking said arm in its lowermost position.

4. A yarn take-up for a knitting machine which includes an arm, one end of which is supported by a horizontal pivot so that it is swingable in a vertical plane, an extension of said arm, means associated therewith for swinging said arm upwardly, resilient means associated with said last mentioned means for energizing said last mentioned means and means for isolating said arm from said resilient means.

5. A yarn take-up for a knitting machine which includes a vertically swingable take-up arm having an extension, means for swinging said arm upwardly which consists of a source of energy which is greatest when the arm is down and which decreases progressively as the arm rises and a lever associated with said source of energy and said extension for applying the decreasing energy of said source to said arm so that its raising power with respect to said arm increases progressively as its inherent energy decreases.

30 6. A yarn take-up for a knitting machine which includes a vertically swingable take-up arm having an extension, resilient means for swinging said arm upwardly which consists of a source of energy which is greatest when the arm is down and which decreases progressively as the arm rises and a lever operatively interposed between said extension and said resilient means for applying the decreasing energy of said source to said arm so that its raising power with respect to said arm increases progressively as its inherent energy decreases.

7. A yarn take-up for a knitting machine which includes a vertically swingable take-up arm having an extension, a tension spring for raising said arm, the inherent energy of said spring being greatest when said arm is down and progressively decreasing as said arm rises and a lever operatively connected to said spring and said extension for causing the raising power of said spring to increase with respect to said arm as its inherent energy decreases.

8. A yarn take-up for a knitting machine according to claim 5 which also includes means operable by the knitting machine for isolating said arm from said swinging means at any desired time.
